UNITED STATES PATENT OFFICE.

ROBERT R. KERMACK, OF PORTSMOUTH, AND EDWARD G. O'DONNELL, OF NEWINGTON,
NEW HAMPSHIRE.

SPRAYER ATTACHMENT FOR HOSE-NOZZLES.

1,299,958.

Specification of Letters Patent. Patented Apr. 8, 1919.

Application filed August 19, 1918. Serial No. 250,555.

To all whom it may concern:

Be it known that we, ROBERT R. KERMACK and EDWARD G. O'DONNELL, citizens of the United States, residing at Portsmouth and 5 Newington, respectively, in the county of Rockingham and State of New Hampshire, have invented certain new and useful Improvements in Sprayer Attachments for Hose-Nozzles, of which the following is a 10 specification, reference being had to the accompanying drawings.

This invention relates to hose nozzles and particularly to sprayer attachments therefor.

15 The general object is to provide a sprayer attachment which may be readily applied to all ordinary forms of hose nozzles and in which the sprayer cone may be shifted into or out of operative position with relation to 20 the nozzle or into a position where it is disposed partly across the mouth of the nozzle, and provides very simple means whereby the yoke supporting the sprayer cone may be held in its adjusted positions without however, preventing the easy shifting of the cone 25 to any other desired position.

A further object is to provide a construction 30 of this character which is very simple in form, has few parts, and may be cheaply made.

Other objects will appear in the course of the following description.

In the accompanying drawings:

Figure 1 is a side elevation of a nozzle and 35 sprayer attachment constructed in accordance with our invention;

Fig. 2 is a fragmentary side elevation showing the means whereby the attachment is connected to the nozzle and showing the 40 nozzle in one of its adjusted positions;

Fig. 3 is a section on the line 3-3 of Fig. 1; and

Fig. 4 is a face view of the portion 10.

Referring to these figures it will be seen 45 that this attachment comprises a short post 10 which is annular in form and which is formed with two opposed resilient clamping members 11. The central opening of the post is screw-threaded for engagement by a 50 screw 12. Preferably the extremities of the resilient clamping members 11 are bent backward to form hooks 13 and preferably a buckle 14 is connected to 1 of the hooks while a strap 15 is connected to the other hook.

55 Mounted upon the rod or screw 12 is an

actuating member 16 which is mounted so that it will turn upon the rod 12, said actuating member being formed with a curved arm 17 which in one position of the attachment arches over the forward end of the 60 nozzle A. This arm 17 at its extremity is formed to provide a disk or plate 18 and to this the spraying member 19 is attached as by screws. This member 19 may be made of wood, metal or any other suitable material and is perfectly circular in cross section with a rounded inner face 20.

The diameter of this member 19 should be slightly greater than the internal diameter 70 of the nozzle A.

By turning the actuating member 16 through the medium of the handle 21 which extends in alinement with the arm 17 and in a direction opposite to the said arm, the spraying member 19 may be carried from an 75 operative position immediately in front of the nozzle to an entirely inoperative position, or to a position where the member 19 is disposed partly across the discharge opening of the nozzle as disclosed in Fig. 2. In order to 80 make a sprayer attachment which may be shifted and yet held in various adjusted positions we form the inner face of the actuating member 16 with a plurality of radially extending ribs 22 and form the outer face of 85 the post 10 with a plurality of radial grooves designed to engage the ribs. A spring 23 mounted upon the screw 12 acts to urge the member 16 against the grooved face of the post 10 and thus holds said member in any 90 adjusted position.

With this construction when the spraying member 19 is disposed immediately in front of the nozzle the rounded face of the member 19 will cause the water to spread laterally in 95 all directions in a divergent spray. If it be desired to cause the water to spray toward one side or the other the actuating member 16 is turned so as to carry the member 19 away from its axial alinement with the nozzle and the rounded face of the member 19 will be disposed at an inclination to the direction of the water and cause the water to spray laterally. Of course, the member 19 may be shifted entirely away from the nozzle 105 so that it will not impede the full discharge of the water.

By providing means for holding the member 19 in any adjusted position the operator 110 can use both hands to control the hose and

this is very important where this is used in connection with fire hose. It is obvious that the spray may be used to protect a fireman entering a burning room and that by spraying the water on the fire the contents of the room will not be so liable to injury as would be the case were the full force of the water used.

It is also to be noted that there is only a single arm 17 attached to the spraying member 19, and that the resilient clamping members 11 have their relatively free hooked ends 13 and the strap and buckle that connect the same together around the nozzle, positioned on that side of the device which is in substantially diametric relation to the post 10 and the actuating member 16 and its arm 17 and handle 21, whereby the said actuating member, arm 17, handle 21 and spraying member or plug 19 will not interfere in any way with the manipulation of the strap and buckle to attach and detach the device, these operations being rendered susceptible of quick accomplishment.

Having described our invention what we claim is:

In a stream deflector for hose nozzles, the combination with a nozzle having spaced annular shoulders integral therewith, whereby an annular groove is formed, of a supporting post, a headed screw threaded in the post, a lever swiveled on the screw for a swinging or oscillatory movement in a plane at right angles to the post, said lever having a pair of arms, one extending toward

the rear and overlying the nozzle constituting a handle, the other being curved and overhanging and extending beyond the mouth end of the nozzle, the extremity of the curved end of said lever having a stream deflector provided with a rounded end face in close position to the mouth of the nozzle, the adjacent parts of the lever and post having means for holding the lever in different adjusted positions, whereby the deflector may be positioned to one side or the other of the mouth of the nozzle, said post being provided with opposed resilient curved clamping members yieldably urging toward and engaging in the groove, a flexible strap detachably connecting the ends of said opposed resilient members, whereby the members may move loosely and swivelly in the groove for supporting the post at right angles to the bottom of the groove, and whereby the deflector may be arranged in a position at right angles to the first position for deflecting the stream at right angles to the first deflection of the stream, and means between the head of the screw and the lever for urging the interengaging parts of the lever and the post together.

In testimony whereof we hereunto affix our signatures in the presence of two witnesses.

ROBERT R. KERMACK.
EDWARD G. O'DONNELL.
